UNITED STATES PATENT OFFICE

158,477

JAR CARRIER

Richard A. Levy, Philadelphia, Pa.

Application February 4, 1948, Serial No. 144,270

Term of patent 3½ years

(Cl. D44—10)

To all whom it may concern:

Be it known that I, Richard A. Levy, a citizen of the United States, residing at Philadelphia, in the county of Philadelphia and State of Pennsylvania, have invented a certain new, original, and ornamental Design for Carrier Combined with a Thermometer, of which the following is a specification, reference being had to the accompanying drawing, forming part thereof.

In the drawing:

Fig. 1 is a side elevational view of a jar carrier, showing my new design; and

Fig. 2 is a plan view thereof.

I claim:

The ornamental design for a jar carrier, as shown.

RICHARD A. LEVY.
